DUPLICATING MACHINE

Marshall Hurst, Ludlow, Ky.

Application June 6, 1935, Serial No. 25,330

7 Claims. (Cl. 101—131)

This invention relates to a duplicating machine of the type wherein gelatinous means is used to receive and transfer an impression.

It is particularly aimed to provide a novel means whereby substantially perfect contact and even pressure is assured between the platen and the paper, a construction wherein a stack of papers in exact position for printing is accommodated; and to generally improve, simplify and render more efficient, the construction and operation of a machine of this general character.

The more specific objects and advantages will in part be pointed out and otherwise become apparent from a consideration of the description following taken in connection with accompanying drawings illustrating an operative embodiment.

In said drawings:—

Figure 1 is a plan view of the duplicator, with the cover removed;

Figure 2 is a right hand end elevation of said duplicator;

Figure 3 is a left hand end elevation of said duplicator;

Figure 4 is an enlarged, central, longitudinal sectional view taken on the line 4—4 of Figure 1;

Figure 5 is a transverse sectional view taken on the line 5—5 of Figure 4;

Figure 6 is a substantially central longitudinal sectional view through the machine, showing a cover in place;

Figure 7 is a detail section taken on the line 7—7 of Figure 1;

Figure 8 is a detail section taken on the line 8—8 of Figure 2;

Figure 9 is a detail perspective view of the retrieving or paper-removing tool, and

Figure 10 is a side elevation of a modified form of the invention.

Referring specifically to the drawings, wherein like reference characters designate like or similar parts, a suitable frame, preferably rectangular and of wood, is used at 10. Within such frame, a paper table 11 is provided having depending

45 braces 12 through which a rod or shaft 13 passes, the table 11 being adjustable transversely of the frame or axially of said shaft 13 and fastened in adjusted positions by means of screws 14 or the equivalent. The table 11 is thus rigidly con-

50 nected to the shaft 13 and the latter is journaled or rocks in openings 15 and in the side walls of frame 10. Shaft 13 is held against displacement through the engagement of lugs 16 in endless grooves 17 of the shaft, which lugs are carried by

55 screws 18 threaded into the side wall of casing 10.

Said paper table 11 is adapted to hold a stack 60 of paper sheets to be printed upon, as at 19 as well as a master sheet uppermost thereon. Such stack 19 is positioned by means of pins 20 rising from the table 11 at suitable locations, supple-

mented by a pair of clips 20a having U-shaped clasp portions 21 detachably engaging one end of such paper table, and having vertical portions 22 for engagement by the paper. The clips 20a, obviously, are adjustable according to variations 5 in the length of the paper of the pile 19. Undue rocking movement of the table 11 is prevented by transverse stop rods 23 of the frame 10.

Coacting with the said paper table 11 is a platen 24 preferably having a depression 25, in 10 which a gelatinous or equivalent body 26 is carried. Said platen at one end, is removably engaged in bifurcations 27 of hinge leaves 28, being fastened therein by screws 29 screw-threaded to the leaves 28 and passing through openings 30 15 in the platen 24. Said hinge leaves 28, by means of horizontal pintles 31 are pivotally connected to attaching leaves 32 fastened as at 33 against the interior of one end wall of said casing 10. Such end wall at the top is slotted or cut away 20 as at 34 to provide clearance, so that the platen may be swung to and from horizontal positions with the platen uppermost or the gelatinous surface 26 uppermost. The paper table at the same end of the device is also cut away as at 35 to 25 provide clearance which will not interfere with working of any of the parts.

In the operation of the device the previously mentioned master sheet is placed uppermost on the pile or stack 19 whereupon the platen is lowered with the gelatinous surface 26 in contact with the transfer surface of the master sheet, whereupon the platen is swung upwardly and outwardly to the extent of 180 degrees, the master sheet adhering to the gelatinous material and 30 being uppermost in the outwardly swung position of the platen. Such master sheet is permitted to remain on the gelatinous material 26 until the ink has been sufficiently absorbed, whereupon the master sheet is retrieved or removed by the use 35 of a tool as disclosed in Figure 9. Such tool comprises a pair of levers 36, pivotally connected by a pin at 37, and having extended gripping jaws 38 of a length best adapted to the width of the paper to be removed or retrieved. The jaws 38 40 are normally urged into separating position by an expansive spring 39 suitably anchored and interposed between the handles 40 of the retrieving tool.

After the gelatinous material has absorbed the 45 ink, and the master sheet then removed, such platen may be moved downwardly against the pile of paper sheets 19 with relative rocking movement occurring between the platen and paper table on the respective axes 31 and 13, an effective 50 printing impression being made on the uppermost sheet of the stack 19, whereupon the platen is again swung 180 degrees and the printed sheet removed by the retrieving tool of Figure 9. Successive operations of the platen effects printing 55 60

of the successive sheets of the stack or pile 19. The invention particularly enables the prestacking or positioning of a plurality of sheets.

A handle of suitable construction and generally designated 41 may be secured to the platen adjacent the free end thereof as by means of screws 42. This handle 41, however, is interchangeable, so as to be applicable to one end of the frame 10, when the device is stored or being moved from place to place. To this end, the said end wall of the casing is provided with screw-threaded openings as at 43, into which the screws 42 may be threaded, as shown in Figure 6.

A suitable cover or closure may be provided across the top of the device if desired as shown at 44. Such cover, for example, may be made of sheet metal, and rests on hooks or the like 45 at one end of the casing, and at the other end of the casing have openings 46 through which the previously mentioned bolts 42 pass.

The platen may be moved out of operative position when desired, and for instance completely detached by removing screws 29. Thereafter, the platen, may be housed in the lower portion 25 of the casing by having its longitudinal edge portions slidably engaged in grooves 48 of rails 49 fastened within the casing and adjacent the longitudinal walls thereof, the retention being aided by frictional engagement with expanded leaf springs 50 fastened at 51 to the rails.

If desired, the platen may be stored in its operative position in which event, L-shaped latches 52 may be swung into retaining engagement therewith as shown in Figure 6. Such latches are 35 pivotally connected against the inner surfaces of an end wall of casing 10 by pivot members 53, and they normally are in intimate contact with such end wall and the adjacent side walls, being out of interfering relation with any of the operating parts.

A modified form of the duplicator is shown in Figure 10 wherein a paper table 60 is provided having upstanding pins 61 thereon positioning a pile or stack of sheets of paper at 62. A platen 63 is adapted to coact with the table 60 and it has a gelatinous body 64 thereon to coact with a master sheet in the same manner as the gelatinous body 26 coacts with a master sheet superposed on the pile of sheets 19. Such platen, however, intermediate its ends, is pivoted by a rod 65 on a frame 66, which in turn is pivoted at 67, to a raised part 68 on the base 60. It will be realized that the frame 66 may be swung 180 degrees or substantially so on the pivot 67 for 55 the same coaction between the sheets 62 and the master sheet and gelatinous body 64 as between the sheets 19, master sheet and gelatinous body 26.

Various changes may be resorted to provided they fall within the spirit and scope of the invention.

What is claimed is:—

1. A duplicator of the class described having a paper table, means pivotally mounting said paper table, a platen, means pivotally mounting said platen, said platen containing a transfer surface facing said paper table and movable into engagement with paper on said table, projections rising from said paper table to position the paper thereon, said projection being outside of the zone of movement of the platen, and means operable to limit the pivotal movement of the paper table.

2. A duplicator of the class described having a paper table, means pivotally mounting said paper table, a platen, means pivotally mounting said platen, said platen containing a transfer surface facing said paper table and movable into engagement with paper on said table, projections rising from said paper table to position the paper thereon, said projection being outside of the zone of movement of the platen, means operable to limit the pivotal movement of the paper table, said paper table at one end thereof having a plurality of removable clasps thereon, said clasps having upstanding portions for abutment by the paper. 5 10

3. A duplicator of the class described comprising a frame, a paper table pivoted within and to the frame, means on said table to position paper sheets, and a platen pivoted to the frame having a transfer surface to engage the paper sheets, said means being outside of the zone of movement of said platen. 15 20

4. A duplicator of the class comprising a frame, a paper table pivoted within and to the frame, means on said table to position paper sheets, a platen pivoted to the frame having a transfer surface to engage the paper sheets, means to adjustably secure the paper table to its axis means, 25 means on the casing limiting movement of the paper table, and means operable to secure the platen against accidental opening. 30

5. A duplicator of the class described comprising a frame, a paper table, hinges pivoting said paper table within and to the frame, means on said table to position paper sheets, a platen pivoted to the frame having a transfer surface 35 to engage the paper sheets, said hinges having bifurcation interfitting with said platen, means detachably fastening the platen in said bifurcation of the hinges, and the casing being cut away adjacent the hinges to enable the platen to be 40 swung outwardly of the casing. 50

6. A duplicator of the class described comprising a frame, a paper table pivoted within and to the frame, means on said table to position paper sheets, a platen pivoted to the frame having a 45 transfer surface to engage the paper sheets, the pivotal mounting means for the platen being hinges secured to the frame, means detachably connecting the platen to said hinges and the casing being cut away adjacent the hinges to enable 50 the platen to be swung outwardly of the casing, rails in the lower portion of the casing, one end wall of the casing being cut away, and said platen being applicable through said cut away portion and to said rails. 55

7. A duplicator of the class described comprising a frame, a paper table pivoted within and to the frame, means on said table to position paper sheets, a platen pivoted to the frame having a transfer surface to engage the paper sheets, the pivotal mounting means for the platen being hinges secured to the frame; means detachably connecting the platen to said hinges and the casing being cut away adjacent the hinges to enable the platen to be swung outwardly of the casing, 60 a handle, means to secure the handle to said platen, a cover for the frame, said cover and adjacent wall of the casing having openings to accommodate said fastenings, whereby the handle is interchangeable. 65 70
